UNITED STATES PATENT OFFICE.

NEAL NIELSEN, OF SPENCER, IOWA.

COMBINATION RUNNING-BOARD FOOTPAD AND LUGGAGE CARRIER.

Application filed November 29, 1926. Serial No. 151,435.

The purpose of my invention is to provide a combination running board foot pad and luggage carrier of simple, durable and inexpensive construction.

More particularly, it is my object to provide such a device having substantially no greater bulk when collapsed than any ordinary running board foot pad, and adapted when in such form to perform the functions and have the appearance of such a foot pad. The device, however, is so connected with the running board and is so constructed that it may be swung from horizontal or prone position to upright position and may be duly expanded for serving as a luggage carrier.

With these and other objects in view, my invention consists in the construction, arrangement and combination of the various parts of my combination running board foot pad and luggage carrier, whereby the objects contemplated are attained, as hereinafter more fully set forth, pointed out in my claims, and illustrated in the accompanying drawings, in which:

Figure 1 shows a side elevation of an automobile equipped with a combination running board foot pad and luggage carrier embodying my invention, the device being shown in the position for use as a luggage carrier.

Figure 2 is a plan view of the running board equipped with two of my devices, one being in position for use as a foot pad and the other in position for use as a luggage carrier.

Figure 3 is an elevation of the device shown mounted on the foot board illustrated in section and viewed from the automobile body.

Figure 4 is a perspective view of the device shown in Figure 3.

Figure 5 is a horizontal, sectional view taken on the line 5—5 of Figure 4.

Figure 6 is a vertical, sectional view taken on the line 6—6 of Figure 4 and illustrating the relationship of my device to the running board.

Figure 7 is a detail, sectional view taken on the line 7—7 of Figure 6 for illustrating the construction of the hinge forming a part of my device; and

Figure 8 is a perspective view of a hook. In the accompanying drawings, I have

used the reference numeral 10 to indicate generally an automobile which has the ordinary running board 11 with the fenders 12 and 12^a at its ends.

It is well known that it is now a common practice to use foot pads on running boards, and that it is also a common practice to use luggage carriers mounted on running boards. Some foot pads interfere with the installation of some luggage carriers.

It is obvious that there are a good many advantages to be attained by combining a foot pad and luggage carrier. The dealer can carry one item instead of two. The user may use a luggage carrier as a foot pad, when he desires, and thus will always find the luggage carrier in place on the car when he needs it.

My luggage carrier has a pair of strap hinges indicated generally at A. The hinge strap members 13 are fastened to the upper surface of the running board 11 by means of bolts 14, screws or any suitable fastening means. The hinge joints are adjacent the outer edge of the running board. The hinge strap members 13 are hinged to the co-acting strap members 15 by means of pintles 16. The strap members are provided with journaling portions 17 to receive the pintles 15.

Parts of these journaling portions 17 are cut away so as to provide on each hinge strap portion 13, an upwardly projecting shoulder 18 and on the hinge strap portion 15, a shoulder 19 arranged so as to coat and engage with each other when the strap portions 15 are raised to vertical position as shown in Figures 4 and 7 for limiting the upward, outward swinging movement of the strap portions 15 and the combination foot pad and luggage carrier supported on them.

My improved device has a foot pad 20 in the form of a plate preferably of metal, having on what is its under surface, the peripheral flanges 21 along its side edges.

The upper surface of the plate 20 is preferably corrugated for instance as indicated at 21^a for appearance sake and for providing a proper roughened surface such as is desirable in the foot pad. The pad plate 20 is preferably longer than it is wide.

The flanges 21 are provided with suitable notches 22 to receive the hinge strap mem-

is collapsed the left hand hook 40 may be extended over the pin 47 for locking the member C in collapsed position.

It will be noted that the parts are so constructed and arranged that if two of my devices are arranged end to end as shown for instance in Figures 1, 2, 3 and 4, the appropriate hook member 40 of one of the devices may be extended over the pin 38 of the adjacent device for thus locking the extensible members B and C of the two adjacent combination devices together.

The parts are preferably arranged so that the extensible members slide with substantial friction and will thus maintain any extended position to which they may be drawn.

I have thus provided a combination running board foot pad and luggage carrier which when in its collapsed position comprises a foot pad of good appearance which does not appear to be a luggage carrier.

Without the necessity for using any tools or special parts, the foot pad can be swung from its lowered position as illustrated at 25 the left hand end of Figure 2 to its last position as illustrated at the left hand end of Figure 2 and the extensible members B and C may be slid outwardly to form luggage carrier parts.

30 The flanges 31 and 34 coact with the cross members 27 to prevent the complete withdrawal of the extensible members from the plate 20.

For a short running board, one of the devices may be used while for a longer running board two may be employed and they may be fastened together in the manner already explained and as illustrated in Figure 3.

40 My device is of comparatively simple and inexpensive construction. It can be made complete at a reasonable price. When the foot pad has been installed on the car, the user does not need to pay any further attention for the necessity of providing a luggage carrier.

The movable portions of the luggage carrier are when not in use, protected from the weather, dirt and accidental injury by being received in and underneath the plate 20.

50 I claim as my invention:

1. In a combination running board foot pad and luggage carrier, a foot pad plate having an annular flange, an extensible luggage carrier member having bars slidably mounted in said flange and an end portion adapted in one position of said member to rest adjacent to the end of said plate, and means for hinging said plate to a running board, whereby when the device rests on the running board for use as a foot pad, the member except such end thereof is received under the plate and between it and the running board, and when the plate is raised to vertical position, said member can be slid-

ably extended to form with the plate a luggage carrier.

2. A combination running board foot pad and luggage carrier comprising a running board foot pad plate, means for hinging the plate to a foot board to move from horizontal position lying on the foot board to vertical position along the outer edge of the foot board and an extensible luggage carrier member slidably mounted on said plate and adapted to form the end of the plate and have its larger portion received between the plate and the running board when the plate is lying on the foot board and to be extended substantially in alignment with the plate 80 when the plate is raised.

3. A combination running board foot pad and luggage carrier comprising a running board foot pad plate, means for hinging the plate to a foot board to move from horizontal position lying on the foot board to vertical position along the outer edge of the foot board and an extensible luggage carrier member slidably mounted on said plate and adapted to form the end of the plate 85 and have its larger portion received between the plate and the running board when the plate is lying on the foot board and to be extended substantially in alignment with the plate 90 when the plate is raised, said hinged means serving as a guide and retaining member for the extensible member.

4. A combination foot pad and luggage carrier, comprising a running board foot pad plate, means for hinging the plate to a foot board to move from horizontal position lying on the foot board to vertical position on the outer side of the foot board and a pair of extensible luggage carrier members 100 slidably mounted on said plate and adapted 105 when in collapsed position to be superposed with relation to each other and the plate and when the plate is lowered to lie between it and the running board and to be slidably extended lengthwise in opposite directions 110 from the pad when the pad is raised.

5. A combination foot pad and luggage carrier, comprising a running board foot pad plate, means for hinging the plate to a foot board to move from horizontal position lying on the foot board to vertical position on the outer side of the foot board and a pair of extensible luggage carrier members 115 slidably mounted on said plate and adapted when in collapsed position to be superposed with relation to each other and the plate and when the plate is lowered to lie between it and the running board means for locking the extensible members in collapsed position, said carrier members being adapted, when 120 the pad is raised, to be slid longitudinally in opposite directions to form extensions of the pad.

6. A combination running board foot pad and luggage carrier comprising a running 130

board foot pad plate, means for hinging the plate to a foot board to move from horizontal position lying on the foot board to vertical position along the outer edge of the foot board, and an extensible luggage carrier member slidably mounted on said plate and having its larger portion received be-

tween the plate and the running board when the plate is lying on the foot board and adapted to be extended substantially in ¹⁰ alignment with the plate when the plate is raised.
